PACKING TRAY

Joseph Hlavka, Milwaukee, Wis., assignor to American Paper & Plastic Products, Inc., Milwaukee, Wis., a corporation of Wisconsin

Filed Nov. 7, 1962, Ser. No. 72,422

Term of patent 14 years

(Cl. D58—13)

FIG. 1 is a top plan view of a packing tray showing my new design, a substantial portion of the tray being illustrated in broken lines to illustrate repetition of the design.

FIG. 2 is an enlarged fragmentary top plan view of a portion of the packing tray shown in FIG. 1.

FIG. 3 is a view taken in section on the line 3—3 of FIG. 1.

FIG. 4 is a view taken in section on the line 4—4 of FIG. 2.

FIG. 5 is a fragmentary top perspective view of one corner of the tray of FIG. 1 on an enlarged scale.

FIG. 6 is a fragmentary bottom perspective view of one corner of the tray of FIG. 1, on an enlarged scale.

I claim:

The ornamental design for a packing tray, substantially as shown and described.
